UNITED STATES PATENT OFFICE.

EUGENE O. MURMANN, OF GLENDALE, CALIFORNIA.

CAN-OPENER.

1,356,651.

Specification of Letters Patent. Patented Oct. 26, 1920.

Application filed November 3, 1919. Serial No. 385,351.

To all whom it may concern:

Be it known that I, EUGENE O. MURMANN, a citizen of the United States, residing at Glendale, in the county of Los Angeles and State of California, have invented new and useful Improvements in Can-Openers, of which the following is a specification.

It is the principal object of this invention to provide a can opener which will cut downwardly, thereby forcing the cut edge inwardly. It is another object of this invention to provide a can opener which will cut close to the edge of a can and will operate on cans of any contour. It is a further object of this invention to provide a can opener which has a fulcrum that may underlie the lid adjacent the portion which is cut, so that cans having little or no lip on the outside of the can adjacent the cover may be cut. It is a still further object to provide a can opener of the class described with means to flatten the cut edge against the can.

These objects will be more fully understood, as will also other objects and corresponding accomplishments of my invention from the following detailed description of an embodiment thereof. For the purpose of this description reference is had to the accompanying drawing, in which:

Figure 1 is an elevation of a can opener as seen from the knife blade side; Fig. 2 is a fragmentary elevation looking at the can opener from the guide side; Fig. 3 is a front elevation of the opener inserted in a can, a portion of the can being shown in section; Fig. 4 is a fragmentary plan view of the opener; and Fig. 5 is an elevation of the opener inserted in a can, a portion of the can being shown in section.

Referring more particularly to the drawing, 6 indicates a handle, preferably of wood, in which is mounted a shank 7. Secured to one side of the shank 7 is a knife blade 8, and secured to the shank upon the opposite side parallel to the knife blade is a guide 9. The guide and knife are conveniently secured to the shank by means of rivets 10.

The guide 9, as shown herein is somewhat in the form of a triangle with one apex directed downwardly away from the shank. The rear edge adjacent the lower apex is warped, as indicated by 11 in Figs. 2 and 3 so as to conform to the curved surface of

the can. The guide is intended to overhang the outside of the can.

The knife blade is in the general form of a hook with the point thereof projecting forwardly as indicated by 12, forming the 60 penetrating tip of the opener. The point also acts as a fulcrum and is warped to conform to the curved shape of the can. The roof of the mouth of the hook has a knife edge 13 formed thereon. The rear of the 65 knife blade has a tail 14 which is warped for the purpose of crowding and bending the cut edge against the can.

In order to cut the lid of a can, the opener is disposed with the penetrating tip resting 70 upon the lid and the handle in an upright position. The tip must be disposed close to the edge so that the guide 9 may be forced over the side of the can as shown in Fig. 3. The tip is then pressed downwardly to penetrate 75 the can. The handle is then tilted so that the opener is in the position shown in Figs. 3 and 5. A cut is made by forcing the handle downwardly toward horizontal position. The knife edge cuts downwardly, the 80 rounded edge of the point of the hook serving as a fulcrum underneath the lid of the can, being warped at the tip, the latter engages the lid inside of the line of severance. The opener is then tilted upwardly, pushed 85 forward and another cut made. This is continued until the lid has been severed.

By means of the construction shown, the lid is cut with downward strokes close to the edge of the can. The cut edge of a can 90 is forced flat against the can by means of the tail 14. The can is left with a smooth upper edge so that there is no danger of the operator cutting himself.

What I claim is:

1. A can opener comprising a handle having a blade secured thereto, said blade being of hook form with the point thereof projecting forwardly of the mouth to provide a fulcrum and having a knife edge formed 100 on the roof of said mouth.

2. A can opener comprising a handle, a blade secured thereto, said blade being of hook form with the point thereof projecting forwardly of the mouth to provide a fulcrum and having a knife edge formed on the roof of said mouth, and a guide secured to 105 said handle and disposed parallel to said blade.

3. A can opener comprising a handle, a 110

blade secured thereto, said blade being of hook form with the point thereof projecting forwardly of the mouth and warped away from said handle to provide a fulcrum and having a knife edge formed on the roof of said mouth.

4. A can opener comprising a handle having a blade secured thereto, said blade being provided with a slot so that an upper and 10 a lower lobe are formed, the upper lobe being provided with a cutting edge opposite the said lower lobe, said lower lobe forming a fulcrum and a piercing point.

5. A can opener comprising a handle, a 15 blade secured thereto, said blade being of hook form with the point thereof projecting forwardly of the mouth and being warped away from said handle to provide a fulcrum and having a knife edge formed on the roof of said mouth, and a guide secured to said handle and disposed parallel to said blade.

6. A can opener comprising a handle, a

blade secured thereto, said blade being of hook form with the point thereof projecting forwardly of the mouth to provide a fulcrum and having a knife edge formed on the roof of said mouth, a guide secured to 25 said handle and disposed parallel to said blade, said blade having a warped tail to bend the cut edge of said can.

7. A can opener comprising a handle, a 30 blade secured thereto, said blade being of hook form with the point thereof projecting forwardly of the mouth and being warped away from said handle to provide a fulcrum 35 and having a knife edge formed on the roof of said mouth, a warped tail on said blade to bend the cut edge of said can, and a guide secured to said handle and disposed parallel to said blade.

In witness that I claim the foregoing I have hereunto subscribed my name this 24th day of October, 1919.

EUGENE O. MURMANN.
